UNITED STATES PATENT OFFICE.

WILLIAM HEIB, OF PHILADELPHIA, PENNSYLVANIA.

DESIGN FOR A CONDUCTOR-FASTENER.

SPECIFICATION forming part of Design No. 31,836, dated November 14, 1899.

Application filed October 2, 1899. Serial No. 732,414. Term of patent 7 years.

To all whom it may concern:

Be it known that I, WILLIAM HEIB, residing in the city of Philadelphia, county of Philadelphia, and State of Pennsylvania, have invented and produced a new and original Design for Conductor-Fasteners, of which the following is a specification, reference being had to the accompanying drawings, forming part thereof.

- o Figure 1 is a perspective view of a conductor-fastener, showing my new design; and Fig. 2 is a longitudinal sectional view thereof.

As shown in the accompanying drawings, the leading or material feature of my design consists of a closed figure comprising the substantially U-shaped sections A and B and the bent strips C, arranged substantially as

illustrated. The sections A and B are provided with the parallel flanges *a* and *b*, which form a channel. The strips C pass through 20 the apertures *c* in the section B and are bent substantially as shown.

Having described my invention, what I claim as new, and desire to secure by Letters Patent, is—

The design for a conductor-fastener substantially as shown and described.

In witness whereof I have hereunto signed my name this 25th day of September, 1899.

WILLIAM HEIB.

Witnesses:

THOMAS S. GATES,
C. N. BUTLER.
